US0D1092044S

(12) **United States Design Patent** (10) **Patent No.:** **US D1,092,044 S**
(45) **Date of Patent:** **** Sep. 9, 2025**

(54) **BACKPACK**

(71) Applicant: **YETI Coolers, LLC**, Austin, TX (US)

(72) Inventors: **Dustin Bullock**, Austin, TX (US); **John Loudenslager**, Austin, TX (US); **Paul Fair**, Denver, CO (US)

(73) Assignee: **YETI Coolers, LLC**, Austin, TX (US)

(**) Term: **15 Years**

(21) Appl. No.: **29/835,562**

(22) Filed: **Apr. 20, 2022**

Related U.S. Application Data

(63) Continuation of application No. 29/700,069, filed on Jul. 31, 2019, now Pat. No. Des. 950,945.

(51) **LOC (15) Cl.** **03-01**

(52) **U.S. Cl.**

USPC **D3/217**

(74) *Attorney, Agent, or Firm* — Banner & Witcoff, Ltd.

CLAIM

The ornamental design for a backpack, as shown and described.

DESCRIPTION

FIG. 1 is a top, front, left perspective view of a backpack showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines depict portions of a backpack and form no part of the claimed design.
